CLAIM

The ornamental design for a strip for a shaving razor cartridge, as shown and described.

DESCRIPTION

FIG. 1 is a perspective view of a strip for a shaving razor cartridge showing our new design;

FIG. 2 is a top view thereof;

FIG. 3 is a bottom view thereof;

FIG. 4 is a left view thereof;

FIG. 5 is a right view thereof;

FIG. 6 is a front view thereof;

FIG. 7 is a rear view thereof;

FIG. 8 is another perspective view of the strip for a shaving razor cartridge with the unclaimed portions of the cartridge removed for clarity;

FIG. 9 is a top view thereof;

FIG. 10 is a bottom view thereof;

FIG. 11 is a left view thereof;

FIG. 12 is a right view thereof;

FIG. 13 is a front view thereof; and,

FIG. 14 is a rear view thereof.

In FIGS. 1-7, the broken lines illustrate the environment. In FIGS. 8-14, the broken lines illustrate portions of the strip for a shaving razor cartridge. None of the broken lines forms part of the claimed design.

1 Claim, 9 Drawing Sheets
